(57) **CLAIM**

The ornamental design for a woodworking sharpening jig, as shown and described.

DESCRIPTION

FIG. 1 is a perspective view of a woodworking sharpening jig showing my present design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a right reference view of the present design, showing a change in the height of the woodworking sharpening jig;

FIG. 9 is a right reference view of the present design, showing that a first joint of the woodworking sharpening jig is deflected forward;

FIG. 10 is a right reference view of the present design, showing that the first joint of the woodworking sharpening jig is deflected backward;

FIG. 11 is a right reference view of the present design, showing that a second joint of the woodworking sharpening jig is deflected forward;

FIG. 12 is a right reference view of the present design, showing that the second joint of the woodworking sharpening jig is deflected backward;

FIG. 13 is a right reference view of the present design, showing that a third joint of the woodworking sharpening jig is deflected forward;

FIG. 14 is a right reference view of the present design, showing that the third joint of the woodworking sharpening jig is deflected backward;

FIG. 15 is a right reference view of the present design, showing that a clamping device of the woodworking sharpening jig is opened; and,

FIG. 16 is a right reference view of the present design, showing a transverse displacement of the woodworking sharpening jig.
